UNITED STATES PATENT OFFICE.

BEZ H. WHITMORE, OF NEW YORK, N. Y.

CIGARETTE.

1,020,864.

Specification of Letters Patent. Patented Mar. 19, 1912.

Application filed June 13, 1911. Serial No. 632,826.

To all whom it may concern:

Be it known that I, BEZ H. WHITMORE, a citizen of the United States of America, residing in New York, borough of Brooklyn, county and State of New York, have invented certain new and useful Improvements in Cigarettes, of which the following is a specification.

This invention relates to cigarettes, and 10 more particularly to those which are made of a filling of tobacco, finely cut, surrounded by an inclosing envelop. And further, to cigarettes made of material which will not burn.

15 Hitherto cigarettes have been made by wrapping tobacco in paper and mostly in the so-called rice paper, but objections to the use of such cigarettes have been very generally made by reason of the fact that the 20 smoking of such cigarettes is accompanied by the poisonous and deleterious nicotin and other poisons which, it is claimed, have their objectionable features aggravated by the burning of the rice paper. Also, hitherto, 25 means have been proposed to obviate the necessity of this rice paper, but these means have proven unsuccessful in that such means consisted of asbestos paper, the object of which was to provide an unburnable wrapper. 30 These cigarettes made of asbestos paper have not proven successful and indeed have been discarded, for the reason that the asbestos paper is composed of asbestos fibers and cloth fibers. Thus on the 35 smoking of the cigarette the ignited tobacco will cause the asbestos to be heated to such an extent as to burn out the cloth fibers in the asbestos paper container. This burning of the cloth fibers, which is an organic substance, results in the formation of gases, 40 unpleasant and injurious. These gases are inhaled with the tobacco smoke and condensed on the walls of the lungs. A further objection to the paper cigarettes hitherto 45 used was that the ashes would break off at times not desired, and a further objection of the asbestos paper cigarettes was that by reason of the stiffness of the same it was impossible to properly break off the burnt 50 part of the same when it was desired to remove the ashes. In consequence thereof the cigarette necessarily lost its character as a cigarette and became so to say, a pipe.

55 My invention has for its object to do away with the objectionable features of the paper and asbestos paper coverings for cigarettes

which have been just pointed out, and for this purpose, my invention consists in providing an asbestos covering which is so arranged that on the burning of the tobacco 60 the ignited portion has free communication with the exterior of the casing throughout the length of the same and continuously during the burning of the tobacco from the tip of the cigarette to the end of the same. 65 This mode of operation is obtained by preparing the wrapper of very finely divided asbestos fibers and binding the same together by a substance, such as starch and water, which acts as a binder to hold the finely 70 divided asbestos threads together, and which are so constituted that on the burning of the cigarette the starch is so converted as not to impede the flow of air through the interstices or cells between the several fibers 75 of asbestos, by reason of which a free communication is maintained between the inner part of the cigarette and the outer part of the same continuously throughout the length of it as the tobacco burns. This cigarette 80 has the great advantage that it is impervious to air while containing the unburned tobacco and pervious to air after the covering has been subjected to the heat of the burning tobacco. Since the ashes occupy a 85 smaller space than the tobacco, a considerable space is left for air to enter. And in the presence of this open space, air will not enter through the pores. The use of the cigarette is unaccompanied by any objectionable burning odors. 90

In the improved cigarette proposed the starch being converted by heat, no gases or smoke are added to the smoke of the tobacco itself, and therefore it is possible by this 95 proposed means to have all the advantages of cigarette smoking. Furthermore, the porosity of the wrapper during the time that it is being subjected to heat, provides an absorber of the poisons, such as nicotin, 100 etc.

A further object of my invention is to so arrange the wrapper as to permit the breaking off of the burnt parts as the cigarette burns, and for this purpose I specially prepare the asbestos wrapper of such thinness that it may be torn off at the desired point, and only at the point where the burning takes place and only on a positive severance. 105 This operation differs from the usual asbestos paper cigarette in that it is capable of being really severed when desired, and from 110

the paper cigarette that it will not sever unless correspondingly manipulated. Although pure asbestos and pure starch are all that is used to make the wrapper, the wrapper is, at the same time, thin enough to be broken from the cigarette and tenacious enough to withstand the tension of cigarette machines, which qualities are due to the materials employed. The action of the heat 10 on the starch and thinness of the wrapper, momentarily suspend the cohering action of the parts while under the immediate action of heat, the parts of the wrapper inwardly of this heat zone and the parts outwardly 15 of the heat zone having substantially their normal cohering qualities. By this property it is possible to sever the wrapper at the part immediately under the action of the heat, and obtain thereby the advantages 20 of the ordinary cigarette.

In the accompanying drawing is shown in Figure 1 a perspective view of my improved cigarette and in Fig. 2 another view showing the severance of the part inclosing the consumed tobacco from the part inclosing the 25 unconsumed tobacco, the parts being shown in approximate size only, in view of the

difficulty of accurately depicting exactly the thinness of the wrapper.

The asbestos covering 10 surrounds the tobacco 11 and is severed at 12 where the tobacco is burning while the severed wrapper 13 surrounds the ashes 14 resulting from the burning of the tobacco. A cork tip 15 may be provided if desired. 30 35

I claim as new and desire to secure by Letters Patent:

A cigarette consisting of a wrapper of asbestos fibers finely ground and starch intimately mixed together and a filling of tobacco, said wrapper coöperating in such a manner with the ignited tobacco that continuous and intimate communication is maintained between the ignited tobacco in the inner part of the wrapper and the atmosphere exterior to the wrapper. 40 45

In testimony that I claim the foregoing as my invention, I have signed my name in presence of two subscribing witnesses.

BEZ H. WHITMORE.
